(57) CLAIM

The ornamental design for an inflatable slide, as shown and described.

DESCRIPTION

FIG. 1 is a perspective view showing our new design;
FIG. 2 is a top plan view thereof;
FIG. 3 is a bottom plan view thereof;
FIG. 4 is a right side elevation view thereof;
FIG. 5 is a left side elevation view thereof;
FIG. 6 is a front side elevation view thereof; and,
FIG. 7 is a rear side elevation view thereof.
The broken lines illustrate portions of the inflatable slide that form no part of the claimed design.
